[57] CLAIM

The ornamental design for a skinning knife, as shown
and described.

DESCRIPTION

FIG. 1 is a side elevation view of a skinning knife showing
my new design, the opposite side being a mirror
image of that shown;

FIG. 2 is a top plan view thereof;

FIG. 3 is a bottom plan view thereof;

FIG. 4 is a front elevational view thereof; and,

FIG. 5 is a rear elevational view thereof.
